UNITED STATES PATENT OFFICE.

MAYHEW E. NOYES, OF CLEVELAND, OHIO, ASSIGNOR TO THE HENDRICKSON MACHINE COMPANY, OF CLEVELAND, OHIO, A CORPORATION OF OHIO.

WORM-GRINDING MACHINE.

1,252,478.

Specification of Letters Patent.

Patented Jan. 8, 1918.

Application filed August 23, 1916. Serial No. 116,526.

To all whom it may concern:

Be it known that I, MAYHEW E. NOYES, a citizen of the United States, residing at Cleveland, county of Cuyahoga, State of Ohio, have invented a certain new and useful Improvement in Worm-Grinding Machines, and declare the following to be a full, clear, and exact description of the same, such as will enable others skilled in the art to which it pertains to make and use the same, reference being had to the accompanying drawings, which form a part of this specification.

This invention relates to grinding machines more particularly of that character adapted to grind the threads of worms or other machine parts having similar threads or teeth, and its object is an automatic machine having a grinding wheel angularly adjustable to accord with the pitch of the thread to be ground and movable longitudinally of the work during the grinding operation at a speed corresponding to the speed of revolution of the work whereby the grinding wheel is maintained in proper engagement with the thread during the grinding operation, and also having indexing mechanism operable at a time when the grinding wheel is out of engagement with the work, to bring a succeeding thread of the worm to position to be ground.

The mechanism for rotating the work holder and thus rotate the worm to be ground, and mechanism for operating the grinding wheel carriage, the indexing mechanism, etc., are identical with like devices or parts shown in my Patent No. 1,161,242, of November 23, 1915, and this invention more particularly relates to the grinding wheel head in combination with such co-operative elements in an organized machine of the character stated, and another object of the invention is a grinding machine having the usual live and dead centers for holding the work and means for rotating the same at predetermined speed and a grinding wheel rotatable at a comparatively high rate of speed for grinding the thread and adapted to be turned about an axis lying in a horizontal plane cutting the longitudinal axis of the work at an angle to accord with the pitch of the thread to be ground.

In said Patent No. 1,161,242, the grinding wheel on being turned at an angle corresponding to the pitch of the thread to be

ground is turned to such position that the point of contact of the wheel with the work is above or below the horizontal plane cutting the axis of the work and, therefore, in the device shown in the said patent means are provided for vertically adjusting the grinding wheel head in order to bring the point of contact with the work in the horizontal plane. With the device which forms the subject matter of this invention, the grinding wheel on being adjusted about an axis in a horizontal plane cutting the axis of the work, the said axis lying in the plane of the grinding wheel and cutting the axis of rotation thereof at a right angle so that at whatever angle possible within the 360 degrees of a circle that the grinding wheel may be set, the point of contact of the grinding wheel with the work never varies.

These and other objects and the several novel features of the invention in its preferred form are hereinafter more fully described and claimed and shown in the accompanying drawings in which—

Figure 1 is an end elevation of a grinding machine embodying my invention.

Fig. 2 is a front elevation thereof.

Fig. 3 is a vertical cross section of the grinding wheel and operating means therefor.

Fig. 4 is a plan view showing the carriage on which is mounted the grinding wheel head.

Fig. 5 is a vertical section on an enlarged scale showing the grinding wheel and operating mechanism.

Fig. 6 is a front elevation of the grinding wheel and supporting means therefor.

Fig. 7 is a detail showing the carriage carrying the grinding wheel.

Fig. 8 is a detail showing a worm and portion of a peculiarly shaped grinding wheel in the relative positions assumed thereby.

Similar characters refer to similar parts throughout the drawing and specification.

The entire operating mechanism of this invention except the grinding wheel head is identical with that described in my former Patent 1,161,242, including the base 10, main drive shaft and clutch mechanism thereon (not here shown), the indexing shaft 13 and gear train connected therewith operating the work holder 14 and the gear train operating the lead screw shaft 51, the

two gear trains having master gears whereby the rotation of the work holder and of the lead screw for moving the grinding wheel carriage longitudinally of the work 5 may correspond and the grinding wheel 97 maintained in proper contact with the thread of the worm during the grinding movement. Likewise, the mechanism including the shaft 130, the gear 132 and stops 10 135 and 136 etc., for limiting the travel of the grinding wheel carriage 82 longitudinally of the work and the carriage is the same as in the former patent.

The carriage is capable of movement toward and from the work holding centers by the gear 120 and vertical shaft operating the cam 115 positioned within a recess in the plate 86 slidable laterally on the plate 82, as will be observed from Fig. 7, and on this 20 plate and adapted to ride in the ways provided is the base 89 of the grinding wheel head 200. It is to be understood that these parts are in the same co-operative relation as described in the said former patent, the 25 only practical difference being in the grinding wheel head 200 and the support 201 for the grinding wheel 97.

As will be observed in Figs. 3, 5, 6 and 7, the head 200 is cylindrical in form and 30 adapted to receive the wheel support 201, also cylindrical in form and fitting therewithin. This base is provided with a removable back plate 202 and is provided at the forward end with a flange 203 by means of 35 which the support is maintained in the head and rotatable therein. The support is held against rotation by means of the set screw 204 and the flange of the back plate 202 may be graduated, as indicated in Fig. 1 by 40 means of which the angle at which the grinding wheel is set may be determined, as is hereinafter described. The support 201 is provided with a forwardly extending portion 205 carrying the grinding wheel shaft 45 206, as will be observed in Figs. 3 and 5, and this shaft 206 is rotatable by means of the spur gear 207 thereon meshing with a similar spur gear 208 on a parallel shaft 209. On the shaft 209 is a bevel gear 210 50 meshing with a bevel gear 211 on the drive shaft 212, mounted in the support 201, the longitudinal axis of the shaft 212 coinciding with the axis of the head 200 and support 201. It is to be observed that this 55 longitudinal axis lies in a horizontal plane cutting the axis of rotation of the work on the center 213, as is shown in Figs. 2 and 3, and also, that this axis cuts through the plane of the wheel and cuts the axis of rotation 60 of the grinding wheel at a right angle thereto. Thus the wheel engages the work in a horizontal plane, cutting the longitudinal axis thereof whether the wheel be turned to position indicated in Fig. 3 or at an angle 65 transversely of the work as indicated in Fig.

1 or 2, as may be required in grinding worms of various pitches or similar machine parts, as spiral gears and the like.

As will be understood from perusal of the former patent above mentioned, the grinding wheel moves longitudinally of the work during engagement of the thread or tooth therewith, and on completing the grinding movement the carriage is moved by means of the cam 115 to withdraw the wheel from engagement with the work, whereupon the carriage and the grinding wheel are moved back longitudinally of the work while out of engagement therewith, and on completion of the reverse movement is again moved to engage the work by means of the cam 115. During this resetting interval, which is considered to involve the time from the interval when the grinding wheel is moved out of engagement with the work till it is again moved into engagement therewith, the work is indexed as in the machine shown in said former patent.

Preferably the grinding wheel is shaped on the edge to engage adjacent flanks of two 90 threads of the worm, the position shown in full lines in Fig. 8 being indicative of the position assumed when out of engagement therewith during the resetting of the wheel and the dotted lines indicating the position 95 when in contact with the worm. It is to be understood, however, that grinding wheels of various shapes may be utilized either for grinding a single flank of a thread or adjacent flanks, as may be desired. 100

In order that the automatic movement of the grinding wheel head may bring the grinding wheel into proper grinding engagement with the work, a screw shaft 220 is mounted on the base 89 and engages the 105 threaded boss 221 carried by the plate 86. This shaft is provided with a bevel gear 222 meshing with a similar gear 223 on a vertical shaft 224, which shaft is provided with a hand wheel 225 at the upper end by means 110 of which it may be rotated. By this arrangement rotation of the shaft 220 slides the base 89 relative to the plate 86 to adjust the grinding wheel in the proper relation to the work. Thus wear of the grinding 115 wheel may be compensated for.

The several shafts of the grinding wheel head are provided with the tight and loose pulleys 215 and 216. The gear ratios are such that the grinding wheel may be rotated 120 at a relatively high rate of speed.

Having thus briefly described my invention, its utility, and mode of operation, what I claim and desire to secure by Letters Patent of the United States is—

1. In a machine for grinding worms, rotatable work holding means, a rotatable grinding wheel movable longitudinally of the work during the grinding interval at a speed to maintain the wheel in proper engagement 130

- with the thread, means for resetting the grinding wheel for successive operations, and a rotatably mounted holder for said wheel, the projected axis of which passes through 5 both the axis of rotation of the grinding wheel and the axis of rotation of the work at a right angle the axis of which cuts the axis of rotation of the grinding wheel and of the work at a right angle.
10. 2. In a machine for grinding threads of worms and the like, rotatable work holding means, a grinding wheel movable longitudinally of the work during the grinding interval at a speed to maintain the wheel in proper engagement with the thread, means 15 for resetting the grinding wheel for successive operations, and a rotatably mounted holder for the wheel, the axis of which is in a horizontal plane cutting the axis of rotation of the work at a right angle and passing through the center of rotation of the grinding wheel.
3. In a machine for grinding the threads of worms or the like, rotatable work holding means, a rotatable grinding wheel movable longitudinally of the work during the operation at a speed adapted to maintain the wheel in proper contact with the thread during the grinding movement, means for 25 resetting the grinding wheel for successive operations, and means for indexing the work during the resetting interval, the grinding wheel being mounted and adapted to be turned about an axis cutting the axis 30 of rotation of the grinding wheel and of the work at a right angle.
4. In a machine for grinding the threads of worms or the like, means for holding the work, and a rotatable grinding wheel adapted to be turned to an angle corresponding with the pitch or angle of the thread and movable longitudinally of the work during the grinding operation, the axis about which the wheel may be turned in adjusting being 45 in a horizontal plane cutting the axis of the work.
5. In a machine of the character described, a rotatable grinding wheel adapted to be brought into and out of contact with the work to be ground, and a support for the wheel rotatable about an axis cutting the axis of rotation of the wheel and of the work at a right angle.
6. In a machine of the character described, a rotatable grinding wheel, a support for the wheel rotatable about an axis cutting the axis of rotation of the wheel and of the work at a right angle, a mounting for said support, and releasable means for 55 securing the said support against rotation therein, the support and mounting being provided with graduations determining the angle at which the grinding wheel is set.
7. In a machine of the character described, 60 work holding means adapted to rotate the work, a rotatable grinding wheel, a support for the wheel rotatable about an axis cutting the axis of rotation of the wheel and of the work at a right angle, a mounting for the support, releasable means for securing the support against rotation therein, a drive shaft, the longitudinal axis of which coincides with the axis of rotation of the support, the grinding wheel being in geared relation with the said shaft, a carriage provided with ways for said mounting, manual means for adjusting the mounting on the carriage toward or from the work to position the wheel relative to the work, automatic means for moving the carriage toward 65 and from the work to bring the wheel into and out of contact therewith, and means for moving the carriage longitudinally of the work, said means including a master gear whereby the movement of the carriage and 70 rotation of the work are so related that the grinding wheel is maintained in desired contact with the work during the grinding operation.
8. In a machine of the character described, 75 rotatable work holding means, a rotatable grinding wheel, a support for the wheel rotatable about an axis cutting the axis of rotation of the wheel and of the work at a right angle, a mounting for the support, releasable means for securing the support against rotation, means for determining the angle at which the grinding wheel may be set, a drive shaft, the longitudinal axis of which coincides with the axis of rotation of 80 the support, and means operatively connecting the drive shaft and grinding wheel.
9. In a worm grinding machine, work holding means, means for rotating the same at a predetermined speed, a rotatable grinding wheel, means whereby the grinding wheel may be turned about an axis cutting the axis of rotation of the wheel and of the work at a right angle, a carriage for the said grinding wheel, automatic means for 85 moving the wheel into engagement with the work, a lead screw in geared relation with the work holding means adapted to move the carriage longitudinally of the work at a speed to maintain the grinding wheel in proper contact with the thread to be ground, automatic means for withdrawing the wheel from the engagement with the work, means for resetting the grinding wheel to original position, and means for 90 driving the grinding wheel.
10. In a machine for grinding the threads of worms, means for holding the work, a grinding wheel movable longitudinally of the work during the grinding operation, 125 means for rotating the work at a speed to maintain the thread in proper contact with the grinding wheel during the grinding movement, means for resetting the grinding wheel for successive operations, means for 130

- indexing the work during the resetting interval, and a support for the grinding wheel rotatable about an axis passing through the plane of the wheel and cutting the axis of rotation of the grinding wheel and of the work at a right angle.
11. In a machine for grinding the threads of worms, means for holding the work, a rotatable grinding wheel, a support therefor, the support being adapted to be turned about an axis passing through the plane of the wheel and cutting the axis of rotation of the wheel and of the work at right angle whereby the wheel may be set at an angle to accord with the angle of the thread to be ground, the wheel being movable longitudinally of the work during the grinding operation, means for rotating the work at a speed to maintain the thread in proper contact with the grinding wheel, automatic means for resetting the grinding wheel for successive operations and automatic means for indexing the work during the resetting interval.
12. In a machine for grinding the threads of worms, means for holding the work, a rotatable grinding wheel adapted to be turned about an axis passing through the plane of the wheel and cutting the axis of rotation of the wheel and of the work at a right angle, automatic means for moving the grinding wheel longitudinally of the work during the grinding operation, means for adjusting the grinding wheel to operate on work of various diameters, means for rotating the work at a speed to maintain the thread in proper grinding contact with the grinding wheel during the grinding move-

ment, automatic means for resetting the grinding wheel for successive operations, and automatic means for indexing the work during the resetting interval.

13. In a machine for grinding the threads of worms and the like, work holding means, a rotatable grinding wheel adapted to be turned about an axis passing through the plane of the wheel and cutting the axis of rotation of the wheel of the work at a right angle whereby the wheel may be adjusted to accord with the angle of the thread to be ground, automatic means for moving the grinding wheel longitudinally of the work during the grinding operation, means for rotating the work at a speed to maintain the grinding wheel in proper contact therewith throughout the grinding movement, said means including a master gear the number of teeth of which is determined by the pitch of the thread to be ground, automatic means for resetting the grinding wheel for successive operations, and automatic means for indexing the work during the resetting interval.

14. In a machine for grinding the threads of worms or the like, work holding means, means for rotating the same, a rotatable grinding wheel for operating thereon, said wheel being adapted to be turned about a fixed center lying in a horizontal plane cutting the longitudinal axis of the work, and releasable means for holding the wheel in the desired position for operating on the work.

In testimony whereof, I sign this specification.

MAYHEW E. NOYES.
